UNITED STATES PATENT OFFICE.

THEODOR FAVARGER, OF PARIS, FRANCE, ASSIGNOR TO THE HOTCHKISS
ORDNANCE COMPANY, (LIMITED,) OF LONDON, ENGLAND.

GUARD-CORDON FOR THE PROTECTION OF SHIPS.

SPECIFICATION forming part of Letters Patent No. 391,362, dated October 16, 1888.

Application filed May 27, 1887, Serial No. 239,522. (No model.) Patented in England February 28, 1887, No. 3,058; in France March 1, 1887, No. 181,881; in Germany March 13, 1887, No. 41,410; in Sweden March 26, 1887, No. 1,056; in Portugal April 27, 1887, No. 1,138; in Italy May 7, 1887, XLII, 325; in Spain May 7, 1887, No. 6,819; in India June 14, 1887, No. 774; in Austria-Hungary October 26, 1887, No. 2,198 and No. 37, and in Norway October 26, 1887, No. 556.

To all whom it may concern:

Be it known that I, THEODOR FAVARGER, engineer, of 21 Rue Royale, Paris, France, have invented certain new and useful Improvements 5 in Guard-Cordons for the Protection of Ships and Harbors, which have been patented in the following countries, namely: France, March 1, 1887, No. 181,881; England, February 28, 1887, No. 3,058; Germany, March 13, 1887, No. 10 41,410; Austria-Hungary, October 26, 1887, No. 2,198/37; Italy, May 7, 1887, No. 325, Vol. 42; Spain, May 7, 1887, No. 6,819; Sweden, March 26, 1887, No. 1,056; Norway, October 26, 1887, No. 556; Portugal, April 27, 1887, No. 1,138; 15 India, June 14, 1887, No. 774; and I, the said THEODOR FAVARGER, do hereby declare the nature of the said invention and in what manner the same is to be performed to be particularly described in and by the following statement thereof—that is to say:

The object of this invention is the protection of vessels of war, of anchorages, and open roadsteads from the attacks of torpedo-boats, war-ships, and other floating means of offense 25 by giving notice of their approach and of their position at night, as well as in foggy weather. For this purpose I establish a cordon made up of convenient lengths of a light strong rope or wire, to which are attached floats for the 30 purpose of buoying the entire length of the same either at or below the surface of the water, and in such a manner that the said lengths may be properly laid out in position for use, as well as also wound promptly upon a reel for 35 storage when not in use. The ends of these lengths of rope or wire are fitted with clamps or shackles, whereby they may be quickly and securely fastened, either to other lengths or to buoys or anchorages. At the junction of 40 these lengths of ropes small buoys are attached by shackling or otherwise, and these buoys are anchored in position by suitable cables and anchors, by means of which the desired or requisite circuit of the cordon is maintained. 45 These buoys are made of a suitable metal, and they are divided internally into compartments or chambers arranged to serve the following

purposes: first, to regulate and maintain their buoyancy; second, to contain inflammable materials intended to light the buoy itself when any part of the cordon is contracted by floating engines of attack; and, third, to contain detachable flasks or floats, which are withdrawn therefrom under circumstances similar to those above mentioned without disturbing the anchored position of the buoy itself, and which flasks contain inflammable material, which ignites on their disconnection from the buoy, and for this purpose the ends of the lengths forming the cordon are attached by 50 means of links or bridles to the said flasks in such a manner that, when by the effect of the pressure exerted on the cordon by the attacking body the ends become released from the buoys, they still maintain their connection 55 with the flasks, which are thereby withdrawn entirely from the buoys and towed by the attacking body. Each flask contains a firing apparatus, which, on its withdrawal, ignites the inflammable material contained in the buoys, 60 and thus marks the position of the attacking body as the flaming flasks are being towed along by the attacking vessel, and in order to insure the buoyancy of these flasks when detached from their respective buoys they are 65 provided with a bag of suitable material, which is extended and inflated by the gases generated by the inflammable material during its combustion, and they are thus prevented from being drawn under water. 70

In order that my said invention be clearly understood, I will describe the same in detail conjointly with the sixteen figures of the accompanying drawings, of which—

Figure 1 is an illustrative view of a guard-cordon surrounding a vessel which it is intended to protect; Fig. 2, an elevation of a part of the cordon with its floats attached; Fig. 3, a front and a side elevation of a float detached; Fig. 4, an elevation of one end of 90 cordon-wire with its shackle; Fig. 5, a plan of the same; Fig. 6, a buoy in elevation; Fig. 7, an anchor with its cable attachment; Fig. 8, a sectional elevation of the buoy on a larger

scale; Fig. 9, a section of same through W W, Fig. 8; Fig. 10, a front view of a hammer-spring; Fig. 11, a section of the said spring with the hammer attached thereto; Fig. 12, a plan, partially in section, of the connection between the cordons and the buoy; Fig. 13, a plan of one of the detachable flasks; Fig. 14, a section of the same through X X, Fig. 8; Fig. 15, a section, d° d°, through Y Y d°; and Fig. 16, a partial front elevation of one of the said flasks with its link.

In the drawings, *a* is the cordon-guard, which is made up of light galvanized-steel-wire rope in lengths, say, of one hundred and fifty yards each. At distances of about two inches this wire rope is provided with short single wires *b*, worked in the strands or otherwise attached thereto, and by means of which small cuniform floats of cork, *c*, are secured to the cordon. These floats are coated with a preservative paint. A single galvanized-iron wire, *d*, is carried along one side or on the top of these floats *c* and caught up or attached to each securing-wire *b*. By this arrangement the cordon is floated just below the surface of the water, and the floats are kept in line and position, and when not in use the cordon may be readily wound upon a reel or coiled. Each end of each length of wire forming the cordon has a thimble, *e*, spliced in it, to which is connected a small galvanized-steel clip or shackle, *f*, and which serve for their attachment either to a buoy or to other lengths of cordon-wire.

g are the small buoys which are secured between the consecutive ends of the cordon-wire *a*, and maintained in place by the shackled ends of the said wires, as well as by cast iron anchors *h* of the clump or mushroom pattern, to which they are attached by a light rope or wire, *i*, one end of which being spliced to the anchor-ring and the other knotted at the length desired to a strap, *k*, fastened to a staple at the bottom of the buoy, as shown in Figs. 6 and 7.

45 The entire circuit of the cordon *a* is made up of the above-mentioned lengths of wire, with buoys *g* inserted at the junctions of the said lengths and duly anchored, as shown in illustration Fig. 1, with a vessel to be protected occupying the center of a circle thus composed, measuring about one thousand yards in diameter and containing a series of buoys placed at about one hundred and fifty yards apart. These figures are merely given by way of illustration, for in reality the only practical limit for the diameter of such a circle will be such a radius at which the light emitted by such a buoy would be readily visible at night from aboard such protected ship.

60 The buoy *g* is made of Muntz metal plates and conical in shape. It is divided internally into two superposed chambers—viz., a lower one, *A*, containing flasks *E*, charged with an inflammable material for lighting the buoy, and an upper one, *B*, filled with cork for the purpose of maintaining its buoyancy, and in which are likewise formed metallic cavities or

chambers *C*, for receiving detachable flasks *D*, filled with inflammable materials. This lower chamber, *A*, contains two earthenware flasks, *E*, shaped to its internal conical contour and provided above with projecting necks that are hermetically sealed. Grooves are cut or formed round the bases of these necks to form planes of weakness, and these flasks are charged with calcium phosphate. A stout stirrup, *d'*, is riveted to the point or lower end of the buoy for the purpose of attaching thereto the mooring-lines *k* *i*. From the ends of this stirrup there project upward two nickel-plated flat steel springs, *l*, provided with hammer-heads on their outer ends, and opposite to these hammer-heads holes are made in the wall of the buoy, which holes are covered with disks of thin lead, *e'*, soldered water-tight. A swell or projection, *e*', is formed at about the middle of the neck of each earthenware flask *E*, and it rests against the inner face of the said leaden disk. If necessary to insure the presence of water in the lower chamber, *A*, small holes may be made through the walls of said chamber, and covers with flexible hinges may be attached internally opposite to said holes.

The extremity of each hammer-headed spring *l* is held or guided laterally in jaws *l'* *l*', which are bolted outside the buoy and serve as a guide for the blow of the hammer when propelled by the spring. A small ring, *e*°, is held between the link *i*' and the spring *l*, in such a manner that as long as it is in place the head of the hammer cannot touch the lead disk *e'*, and the strength of the spring *l* is such that a pull of, say, one hundred pounds, is necessary to draw the ring away from the jaws and off the end of the spring *l*, whereby the hammer, impelled by the spring, strikes the plate *e'* and breaks the neck of the flask *E*. To guard against the accidental release of the spring *l* and its hammer during the laying and handling of the cordon-guard, a stick of sal-ammoniac or other material readily soluble in water, *z*, is inserted in and across the jaws *l'* *l*' opposite to a small head raised on the ring *e*°, (see Figs. 12 and 8,) which will prevent such accidental release of the spring until such time as the entire cordon is connected and laid, while very shortly afterward the sal-ammoniac is melted out by the water and the apparatus is in a position to fulfill the intended requirements.

When the proper strain has been brought on any part of the floating cordon-guard, the hammer-head, in connection with such length of the cordon, is drawn back until the ring *e*° slips away from the jaws *l'* and off the spring *l*, the hammer of which is thus liberated and projected forward by the spring *l*, and, striking the lead disk *e'*, breaks the neck of the flask *E* inside the buoy, whereby the sea-water coming in contact with the calcium phosphate ignites the same, and the flaming gases produced find an exit through the vertical tube *v*, fixed in the center of the buoy.

The upper end of the bridle or link *i*' is jointed to the metal flask *D*, which is housed

in the chamber C of the buoy, which latter is roughly cylindrical and traverses the buoy horizontally. This flask is filled with calcium phosphate, and its face is closed and hermetically sealed by a glass plate, ℓ , just inside of which is hung a firing-hammer, m , on an axis, n , which is set at tension by a spiral spring, o , passed over one end of the said axis. This end likewise carries a small lever, p , which projects upward outside the flask and serves for cocking the hammer, and which, when set, is inserted with the flask in a groove, g^x , made in the wall of the chamber C, and maintains the hammer cocked ready for action on the withdrawal of the flask from its chamber.

A rubber bag, s , is secured hermetically over the inner end of the flask D, and is closed at its outer end by a metal plate, t , pierced with a small central hole, t^x , and a small hollow keel, u , is fixed to the under side of the flask.

When the strain on the cordon a , produced by the attacking vessel, has disconnected the ring e^x from the spring l , as before explained, the link i will remain connected to the detached end of the cordon and will extract the flask D from its chamber C, the lever p is thereby liberated, and consequently the hammer m is propelled by the spring o and strikes and breaks the glass-plate ℓ , and the calcium phosphate contained in the flask is ignited by the irruption of the sea-water, whereby gases are produced which inflate the bag s and issue in the shape of a flame through the hole pierced in the back plate, t . The detached portion of the cordon will naturally be bent around and cling to the attacking vessel, so as to be towed along by it, and as this is done the inflated bag keeps the flask D from being drawn under water and the flame escaping freely therefrom marks constantly the position of the attacking vessel.

Having now particularly described and as-

certained the nature of this said invention and in what manner the same is performed, I declare that what I claim is—

1. The combination, with the floating cordon, of buoys detachably connected thereto and carrying contained in frangible flasks inflammable material which ignites by contact with sea water, and connections, substantially such as described, for rupturing said flasks, so as to admit water thereto by pressure against the cordon, substantially as described.

2. The combination, with the cordon, of the moored buoys connected thereto and provided at their upper ends with buoyant material, at their lower ends with material which ignites by contact with sea-water, and with the vertical passage v , by which the flame produced by the burning of said material issues from the top of the buoy, substantially as described.

3. The combination, with the cordon, of the buoys detachably connected thereto, the removable expandible flasks D, carried by said buoys and independently connected to said cordon and containing material which ignites by contact with sea-water, substantially as described.

4. The combination, with the cordon and the buoys containing material which ignites by contact with sea-water, of the springs l , forming a yielding detachable connection between said buoys and the cordon, and the interposed sticks z , of soluble material, for making said connection temporarily rigid, substantially as described.

In witness whereof I have hereunto signed my name in the presence of two subscribing witnesses.

THEODOR FAVARGER.
